IMPROVEMENT IN BAG HOLDER.

CHARLES J. BARNEY, OF EDGARTOWN, MASSACHUSETTS.

Letters Patent No. 60,121, dated December 4, 1866.

SPECIFICATION.

TO ALL WHOM IT MAY CONCERN:

Be it known that I, CHARLES J. BARNEY, of Edgartown, in the county of Dukes, and State of Massachusetts, have invented a new and improved Bag Holder; and I do hereby declare that the following is a full, clear, and exact description thereof, which will enable those skilled in the art to make and use the same, reference being had to the accompanying drawings, forming part of this specification, in which—

Figure 1 is a vertical central section of my invention, taken in the line $z z$, fig. 2.

Figure 2, a plan or top view of the same.

Similar letters of reference indicate corresponding parts.

This invention relates to a new and improved device for holding bags while the same are being filled; and it consists in the employment or use of a hopper fitted in a platform supported by a frame, and arranged in the manner substantially as hereinafter fully shown and described; whereby bags may be filled with the greatest facility by a single individual.

A represents a frame on which a horizontal platform, B, is secured; the latter has a hole or opening, C, made in it, which is represented of oval form in fig. 2, and this form will probably be the most desirable one. The sides of the opening C are or may be inclined slightly; and D is a hopper of flaring form, having a flange, E, at its lower end to fit in the opening C, the flange corresponding in shape with the opening. The hopper D, which may be constructed of sheet metal, is attached to the platform B, by a hinge, δ , as shown in fig. 1, so that the hopper may be turned over out from the opening C, when desired; the flange E being slightly taper, corresponding to the inclination of the side of said opening. F is a platform which, when required for use, is fitted in the frame A, resting on bars, b, therein.

The device is used as follows: In filling long bags the platform E is removed from frame A, and the hopper D turned over out from the opening C, so that the upper end of the bag, G, may be fitted over the flange, E. The hopper D is then turned down, and the upper end of the bag is secured between the flange and the side of the opening, C, the lower end of the bag resting upon the floor, as shown in red. The bag may then be readily filled, and when filled removed from the frame with the greatest facility. When short bags are to be filled, the platform E is placed in the frame to support them, as shown in black in fig. 1. The device is extremely simple and efficient, and may be constructed at a small cost.

I claim as new, and desire to secure by Letters Patent—

The frame A, provided with a platform B, having an opening, C, made in it to receive the flange or lower part of the hinged hopper, D, and used in combination with a removable platform, E, substantially as and for the purpose specified.

CHARLES J. BARNEY.
